UNITED STATES PATENT OFFICE.

FRANKLIN A. STEARN, OF PATERSON, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed April 11, 1921. Serial No. 460,318.

To all whom it may concern:

Be it known that I, FRANKLIN A. STEARN, a citizen of the United States of America, residing at Paterson, in the county of Passaic, State of New Jersey, have invented certain new and useful Improvements in Telephone-Exchange Systems, of which the following is a full, clear, concise, and exact description.

10 This invention relates to telephone exchange systems and particularly to systems wherein talking connections between subscribers' lines are established in part by means of machine switching apparatus and 15 in part by the use of equipment manipulated by central office operators.

In certain semi-automatic systems the subscribers' lines are terminated in jacks at operators' positions in the central office. So 20 far as the subscriber is concerned his line is identical in all respects to an ordinary manual line. To make a call he removes his receiver from its switch hook and communicates the wanted number to the responding 25 operator. At the central office, too, the duties of the operator correspond in some respects to those of the usual manual operator. She answers the calling line by inserting the plug of an idle cord circuit at her 30 position in the jack of the calling line. On receiving the number of the desired line from the calling party she then proceeds to record the same on a set of keys, which determine the operation of a register 35 controlling mechanism to govern the selective operation of automatic switches in the extension of the call. In order that the operator may be relieved of the manipulation of listening keys, each time a call is answered, 40 for connecting her telephone set to the calling line and disconnecting it therefrom certain instrumentalities are used to accomplish the same automatically.

The object of the present invention is the 45 provision, in a system of the above described character, of an arrangement consisting of a combination of relays, the function of which is to instantaneously connect the operator's head-set to and disconnect the same from the connecting circuits at her position and which also serves under certain conditions to prepare for the disassociation of the register sender from the particular circuit with which it may be associated at the time.

A feature of the invention relates to the provision of connecting relays, one for each of the cord circuits at an operator's position, the relay of a particular cord being operative when the cord is taken for use to connect the operator's telephone set thereto and means, when a second cord is taken for use, for shunting out the relay of the first cord and permitting the connecting relay of said second cord to operate to transfer the operator's set from the first to the second cord circuit.

Another feature of the invention relates to means operated simultaneously with the operation of the connecting relays in the transfer of the operator's set from the first to the second cord circuit, while a register sender is attached to such first cord, for setting up a condition in advance which subsequently causes the sender to be disassociated from the first cord after said sender has completed its switch-controlling functions.

A still further feature has to do with the provision of a marginal relay, which operates when included in a circuit extending through more than one of the connecting relays individual to the cords, during the transfer of operator's set from one cord to another, and which marginal relay in operating sets up in advance a condition for later causing the release of the register sender when said sender has completed its switch controlling functions.

Such other and further features as are contemplated in the present invention will become more fully understood from a consideration of the following detailed description and the appended claims.

In the drawing Figs. 1 to 7 inclusive, when the corresponding sheets are arranged in the order pictured in Fig. 8, disclose a telephone exchange system embodying the subject matter of the invention. Fig. 1 shows an operator's position at which incoming subscribers' lines terminate in answering jacks, one such line being illustrated. One of a plurality of cord circuits is also shown in this figure by means of which the operator responds to calling lines, each of such cord circuits terminating in the brushes of a district selector switch.

Fig. 2 illustrates the operator's telephone set and the necessary equipment whereby

said set is connected to and disconnected from the cord circuits at her position in response to certain acts on the part of the operator, and also automatically in response to certain conditions brought about in the progress of establishing connections.

Fig. 3 shows one of a plurality of cord finder switches for attaching the associated register sender with the cords at the operator's position, together with an allotter switch for allotting an idle cord finder sender and register sender unit for use.

Fig. 4 shows partially the office keys on the operator's keyboard together with the office registers of a register sender, to a plurality of which senders said keys are common.

Fig. 5 shows a portion of the four rows of numeral keys on the operator's keyboard and the corresponding numerical registers of the same register sender.

Fig. 6 illustrates a set of counting relays and the sender sequence switch which co-operate to control the setting of the selective switches in accordance with the designations represented on the registers.

Fig. 7 shows an office selector switch to which calling lines are extended by way of the district selector shown in Fig. 1. This figure also illustrates, by the schematic showing of the brushes, an incoming and a final switch which participate in the establishment of a complete connection through to the called subscribers' lines, one of which is shown.

As hereinbefore mentioned the calling subscribers' lines terminate in jacks at answering operators' positions. The operator is provided with a plurality of cord circuits one end of which terminates in an answering plug and the other in the brushes of a district selector switch. In responding to a calling line, the indication of which is given to her in the usual manner by means of a calling lamp, the operator inserts the plug of an idle cord circuit in the jack of said line. This act on the part of the operator immediately causes her telephone set to be automatically connected to the cord circuit taken for use in order that she may converse with the calling subscriber to ascertain his wants. The connection of the operator's telephone set to the cord circuit is made by means of a quick operating device, such as a relay, and is maintained until the establishment of the desired connection has progressed to a certain point, at which time her telephone set is automatically disconnected by the register sender, or until the operator actuates a listening out key in case for any reason she wishes to hasten the disconnection of her talking equipment.

Furthermore, the act of inserting the plug of the cord circuit in the jack of the

calling line initiates the operation of an allotted idle cord finder and register sender unit, such as the one shown in Figs. 3, 4, 5 and 6. The cord finder 340, which has access to sets of terminals in its bank representing all of the cord circuits at the operator's position, is driven in a hunting movement to find the set of terminals identifying the particular cord that the operator has taken for use. The cord finder in finding the proper cord circuit associates therewith the register sender unit upon which the operator records the designation of the called line, and which thereafter serves to control the operation of the selective switches to extend the calling line to the desired office and thence to the called line therein.

The operator's keyboard, which is common to all of the register sender units of her position, is comprised of two distinct parts. The first part comprises what may be called the office or tandem keys. In Fig. 4 there is illustrated three rows of such keys, 400, 401 and 402.

By actuating the different combinations of these three rows of keys the operator may cause the setting of the class and office registers 404, 405, 406, 407 and 408 in accordance with the code designations identifying the various offices in the telephone area to which connections from the office here illustrated may be extended.

In other words, that part of the total designation which represents the office containing the called line may consist of three characters, either numerals or letters, and according to the code of these characters the office keys, shown in Fig. 4, are adapted to produce the record on the office registers to in turn control the setting of the district and office switches, Figs. 1 and 7, to extend the connection to the desired office.

Where the traffic to certain outlying offices is comparatively heavy and a large number of calls are handled in the course of a day, it is found desirable to provide a single key for such offices to take the place of the combination of three keys in the rows 400, 401 and 402. Such a key is shown at 403 and serves the same purpose in setting up the entire record on the office registers as would be accomplished by the depression of a key in each of the three rows 400, 401 and 402. The second part of the operator's keyboard consists of four rows of numerical keys 500, 501, 502 and 503 on which the number of the desired line is recorded to effect the setting of the numerical registers, 504, 505, 506 and 507.

The stations register 508 is provided and where the called line is one containing a plurality of substations, stations keys may also be installed at the operator's position to determine the selection of ringing current. In the present disclosure, however,

the stations keys have been omitted and a single start key 520 is used for a purpose hereinafter to be explained.

The operator having received the name of the office and the number of the called line therein from the calling subscriber, now proceeds to set up the code on the office keys representing such office and also to record the numerical designation of the line on the numerical keys. With the registers in their corresponding positions the sender next becomes effective to control the setting of the switches to establish the connection.

The district and office selector switches shown in full in Figs. 1 and 7, and also the incoming selector represented diagrammatically by the brushes 727, 728 and 729, and the final selector represented diagrammatically by brushes 733, 734 and 735 may be of the general type and construction shown in the patent to Craft and Reynolds 1,123,696 issued January 5, 1915.

The cord finder switch illustrated in Fig. 3 is also of the same general character except that in this case a single set of brushes is mounted on the shaft and driven by the source of power over the terminals of the bank.

The sequence switches 110, 710 and 310, which control the circuits of the district selector, office selector and cord finder switches, are of the well known type disclosed in the patent to Reynolds and Baldwin 1,127,808 issued February 9, 1915. The sender sequence switch 610, the allotter switch 320 and the several registers shown in Figs. 4 and 5 are also of the same construction. Where the cord finder sequence switch 310 and the allotter sequence switch 320 both occur on the same sheet, confusion is avoided by locating all contacts controlled by the latter sequence switch within the area set off by broken lines in the upper right-hand corner. In Fig. 4 the several contacts belonging to the class register 404 and the office registers 405, 406, 407 and 408 are segregated respectively within the spaces set off by the vertical broken lines. The same plan is used in Fig. 5 with respect to the contacts belonging to registers 504, 505, 506, 507 and 508.

With the foregoing general description of the system in mind, it is believed that a more thorough understanding of the invention may now be had by considering the detailed operation involved in the establishment of a complete connection. For this purpose it will be assumed that a calling subscriber, such as the subscriber at substation 100, desires to communicate with the subscriber of line 740.

The operator responds to a call initiated by a subscriber.

65 The subscriber at substation 100, on ini-

tiating a call, completes a circuit for the line relay 101 extending over the armatures and contacts of cut-off relay 102 and the loop of the line. Relay 101 completes a circuit for the calling line lamp 107, the illumination of which notifies the operator that a call is awaiting her attention. The operator thereupon seizes plug 104 of an idle cord circuit at her position and inserts it in the jack 103 of the calling line. A circuit is thereby completed from battery through the winding of relay 102, sleeve of jack 103, sleeve of plug 104, conductor 165, normal contacts at the right-hand armature of relay 208, winding of relay 109 to ground, causing the energization of both relays 102 and 109. Relay 102 opens the circuit of relay 101, which in turn causes the effacement of lamp 107. Relay 109 completes a circuit from subbattery through its right-hand armature and contact, conductor 170, winding of relay 200 to ground.

It may be well to note at this point that both main and subbattery are used in this system, the difference being indicated in the drawing by showing twice the number of cells for the main battery as for the subbattery. The positive pole of the main battery is grounded, whereas the sub-battery has its negative pole grounded. Wherever, in tracing circuits, the subbattery is involved the same will be referred to as such, but in describing circuits which include the main battery no special mention will be made thereof.

Relay 200 energizes in the above traced circuit and closes a circuit from battery through the winding of marginal relay 206, left-hand armature and contact of relay 207, winding of relay 202, left-hand armature and back contact of relay 201 to ground at the left-hand armature and contact of relay 200. Relay 202 becomes energized and completes a circuit in parallel to the one just traced extending through the winding of relay 203 to ground at the contact and right-hand armature of relay 202. Relay 203, however, does not energize at this time due to the fact that it is shunted by the direct circuit to ground at the left-hand armature and contact of relay 200. Moreover, relay 206, which is also included in the circuit of relays 202 and 203, is not operated since it is marginal and does not receive sufficient current to attract its armatures. Relay 202 also completes a circuit from battery through the winding of relay 204, winding of relay 205 to ground at the contact and right-hand armature of relay 202. Relays 204 and 205 operate and a circuit is closed from subbattery through the right-hand armature and contact of relay 109, conductor 170, outer right-hand armature and contact of relay 205, winding of relay 201 to ground. Relay 201 actuates and locks

- up through its right-hand armature and front contact independently of the outer right-hand armature and contact of relay 205. Relay 201, on attracting its left-hand armature, opens the shunt circuit around relay 203, permitting this latter relay to energize in series with relays 206 and 202. The function of relay 203, which, it will be noted, is operated immediately following 5 the insertion of the plug in the jack, is to connect the operator's telephone set 210 to the strands of the cord circuit taken for use in answering the calling subscriber's line. The operator may now converse with the 10 calling subscriber to learn the number of the line with which he wishes connection. Talking current is supplied to the calling line in a circuit from battery through the lower left-hand winding of repeating coil 117, winding of supervisory relay 115, conductor 140, front contact and inner left-hand armature of relay 203, lower contacts of ringing keys 214, 213, 212 and 211, outer right-hand armature and contact of relay 15 203, contact and right-hand armature of relay 200, conductor 105, tip of plug 104, tip of jack 103, over the loop of the calling line, ring of jack 103, ring of plug 104, conductor 106, front contact and outer left-hand armature of relay 203, upper contacts of ringing keys 214, 213, 212 and 211, inner right-hand armature and front contact of relay 203, conductor 139, upper left-hand winding of repeating coil 117 to ground. 25 Talking current is furnished to the operator's telephone set from a local source as will be obvious from an inspection of the drawing.
- As soon as relay 202 operates a circuit is 30 completed from battery through the winding of the power magnet of sequence switch 110, conductor 167, left-hand armature and front contact of relay 202, conductor 166, lower contacts of sequence switch spring 40 45 141 to subbattery and ground. Sequence switch magnet 110 is energized in this circuit and advances the several sequence switch springs out of position 1 and into position 2. In position 2 a circuit is closed for the calling supervisory lamp 131 which 50 extends from subbattery through the lower right-hand contact of sequence switch spring 171, lamp 131, resistance 132 to ground. Lamp 131, however, remains extinguished since it is shunted by means of a circuit from subbattery through the lower right-hand contact of sequence switch spring 171, upper right hand contact of said 55 springs, armature and contact of supervisory relay 115, which is operated due to the fact that the calling subscriber's receiver is off the switch hook, resistances 133 and 132 to ground. In position 13 of sequence switch 110, when spring 171 is open at its 60 upper right contact, the shunt circuit of

lamp 131 leads through the right contact of relay 112. In position 2 of sequence switch 110 a circuit is closed from subbattery through lamp 125, resistances 123 and 122, upper right-hand contact of sequence switch 70 75 spring 127 (2+11), lower left-hand contact of said sequence switch spring (2+16) to ground. The lamp 125 burns steadily in this circuit which is maintained until after sequence switch 110 leaves position 11 following the completion of the function of the register sender. The lighted condition of lamp 125 serves as an indication to the operator that the apparatus is ready for the attachment of a sender. The lamp will continue to burn until the sender is later released. 80

Association of the sender with the operator's cord circuit.

As soon as sequence switch 110 reaches position 2 a circuit is completed from battery through the winding of relay 301, Fig. 3, lower left-hand contact of sequence switch spring 308 (1+2), upper right-hand contact of sequence switch spring 308 (1+1½), conductor 360, armature and contact of relay 204, contact and left-hand armature of relay 206, upper left-hand contact of sequence switch spring 143 (8+2) lower right-hand contact of sequence switch spring 143 (2+6) to subbattery and ground. Relay 301 operates in this circuit and closes a circuit from subbattery through its right-hand armature and front contact, lower right-hand contact of sequence switch spring 307 (1), winding of sequence switch magnet 310 to battery and ground. Sequence switch 310 moves from position 1 into position 2. As the sequence switch leaves position 1½ the original circuit of relay 301 is opened at the upper right-hand contact of sequence switch spring 308 but relay 301 remains energized in position 2 in a circuit which extends through the upper left-hand contact of sequence switch spring 308 (1½+17), back contact and right-hand armature of relay 300 to subbattery and ground. In position 2 of sequence switch 310 a circuit is closed from battery through the winding of the updrive power magnet 336, lower left-hand and upper right-hand contacts of sequence switch spring 316, front contact and right-hand armature of relay 301 to subbattery and ground. Power magnet 336 energizes in this circuit and presses the depending portion of the shaft 340 against the updrive power roll, causing the brush shaft of the cord finder to move upwardly. When the brushes of the cord finder encounter the terminals representing the cord circuit taken for use by the operator, a circuit is closed from battery through the winding of relay 300, upper left-hand contact of sequence switch spring 309 (2), brush 347, terminal 95 100 105 110 115 120 125

353, conductor 359, sequence switch spring 108 (2), back contact and left-hand armature of relay 120, back contact and right-hand armature of relay 113, lower right-hand contact of sequence switch spring 135 (2+18) to subbattery and ground. The relay 300 attracts its armatures and closes a holding circuit for itself leading through the upper right-hand contact of sequence switch spring 309 (2+16), contact and left-hand armature of relay 300, brush 345, terminal 351, conductor 357, lower left-hand contact of sequence switch spring 137 (2+11), upper left-hand contact of sequence switch spring 137 (2+16½), back contact and left-hand armature of relay 113 to subbattery and ground. Relay 300 also at its right-hand armature opens the original circuit of relay 301. Relay 301, however, remains energized in the following circuit until the brushes of the cord finder switch are accurately centered on the selected set of terminals: battery, through the winding and contact and left-hand armature of relay 301, commutator 338, brush 339 to subbattery and ground. When the brushes are accurately centered this momentary holding circuit is opened and relay 301 becomes deenergized, opening, at its right-hand armature, the circuit for the power magnet 336. The cord finder switch is brought to rest and at the same time a circuit is closed as follows for moving the sequence switch 310 out of position 2 and into position 3: battery, through the winding of sequence switch magnet 310, lower left-hand contact of sequence switch spring 307 (2), back contact and right-hand armature of relay 301 to subbattery and ground.

40 *The operator records office and numerical designations on keyboard.*

The register sender has now been attached to the cord circuit and is in readiness to receive the record of the called subscriber's line. After communicating with the calling subscriber and learning the name of the office and designation of the desired line therein, the operator proceeds to make a record thereof on her office and numerical keys. It will be assumed that the name of the office which contains the called line 740 is represented by the single office key 403 on the operator's keyboard and that the numerical designation of said line is 9744. Accordingly, the operator depresses the office key 403 and also the thousands key 516, the hundreds key 517, the tens key 518, the units key 519 and the start key 520. These keys are all of the well-known locking type, which remain in their depressed condition until released by the energization of the key release magnets 420, 421, 422, 423 and 424.

85 The actuation of the office key 403 closes a circuit from subbattery through the wind-

ing of relay 414, middle contacts of key 403, windings of relays 415 and 416, conductor 441, lower left-hand contact of sequence switch spring 327 (1), winding of relay 303, upper contact of sequence switch spring 333 70 (1), contact of sequence switch spring 334 (1), upper left-hand contact of sequence switch spring 322 (2+6) to battery and ground.

It should be noted at this time that the allotter switch 320 is in position 1, which is the position for allotting the register sender unit shown. As will be taken up herein-after, the allotter is designed to take care of three different register senders, the remaining two being allotted in positions 6 and 12 respectively.

The depression of key 403 also completes a circuit from subbattery through the winding of relay 417, right-hand contacts of key 403, windings of relays 418 and 419, conductor 441, and thence to battery as described. Relay 416 completes a circuit from subbattery through its contact and armature, right-hand armature and back contact of relay 409, winding of the class register magnet 404, upper left-hand contact of sequence switch spring 324 (2+3) to battery and ground. Relay 416 also completes a circuit from subbattery through its contact and armature, armature and back contact of relay 410, winding of the magnet of district brush register 405, upper right-hand contact of sequence switch spring 324 (2+3) to battery and ground. Relay 416 closes a third circuit from subbattery through its contact and armature, armature and back contact of relay 411, winding of the magnet of district group register 406, lower right-hand contact of sequence switch spring 324 105 (2+4) to battery and ground. Relay 419, on energizing, completes a circuit from subbattery through its contact and armature, contact and right-hand armature of relay 412, winding of the magnet of office brush register 407, lower left-hand contact of sequence switch spring 324 (2+5) to battery and ground. Relay 419 closes a second circuit from subbattery through its contact and armature, armature and back contact of relay 413, winding of the magnet of office group register 408, upper left-hand contact of sequence switch spring 323 to battery and ground. The class and office registers are energized in these circuits and commence to 110 rotate to search for the positions represented by the depressed office key 403. When the class register 404 reaches position 2 a circuit is completed from subbattery through the left-hand contacts of key 403, upper right-hand contact of spring 425, winding of relay 409, lower right-hand contact of sequence switch spring 329 (1), winding of relay 303, upper contact of sequence switch spring 333 (1), upper contact of sequence

115 120 125 130

switch spring 334, upper left-hand contact of sequence switch spring 322 (2+6) to battery. Relay 409 operates and opens the driving circuit of the class register 404, whereby said register comes to rest in position 2. When the district brush register 405 reaches position 4 a circuit is completed from subbattery through the contact and armature of relay 414, lower right-hand contact of spring 426 (4) winding of relay 410, lower left-hand contact of sequence switch spring 329, and thence to battery and ground over the circuit above traced. Relay 410 attracts its armature and opens the circuit of register 405, which thereupon stops in position 4. When register 406 reaches position 1 a circuit is closed from subbattery through the armature and contact of relay 415, upper left-hand contact of spring 427 (1), winding of relay 411, lower right-hand contact of sequence switch spring 328, and thence to battery and ground. Relay 411 opens the circuit of register 406 permitting this register to stop in position 1. When register 407 arrives in position 4 a circuit is closed from subbattery through the contact and armature of relay 417, lower right-hand contact of spring 428 (4), winding of relay 412, upper left-hand contact of sequence switch spring 328 (1), and thence to battery and ground. Relay 412 opens the circuit of register 407, which consequently stops in position 4. Similarly, when register 408 reaches position 3 a circuit is completed from subbattery through the armature and contact of relay 418, lower right-hand contact of spring 429 (3), winding of relay 413, upper right-hand contact of sequence switch spring 328 to battery and ground. Relay 413 opens the circuit of register 408 which comes to rest in position 3. The circuits above traced for the relays 409, 410, 411, 412 and 413 all extend through the winding of relay 303, and thence to battery by way of the upper left-hand contact of sequence switch spring 322. Relay 303 consequently energizes and at its left-hand armature and contact supplies battery current for itself and the relays 409, 410, 411, 412 and 413 by way of the upper contact of sequence switch spring 333. This substitute holding circuit is provided in order that relay 303 and the several stop relays 409, 410, etc. may be held energized after the cord finder sequence switch 310 has left position 6.

As soon as the first two registers, namely the class register 404 and the district brush register 405, have been positioned, the cord finder sequence switch 310 is moved out of position 3 and into position 4. The circuit for advancing sequence switch 310 may be traced from battery through the winding of the magnet of said sequence switch, lower right-hand contact of sequence switch spring 306 (3), contact and left-hand arma-

ture of relay 409, front contact and armature of relay 410, armature and contact of relay 416 to subbattery and ground. When the district group register 406 reaches its set position, the cord finder sequence switch 310 is moved out of position 4 and into position 5 by means of a circuit from battery through the winding of magnet 310, lower left-hand contact of sequence switch spring 306 (4), front contact and armature of relay 411, armature and contact of relay 416 to subbattery and ground. When the remaining two office registers 407 and 408 are positioned the cord finder sequence switch 310 is advanced into position 6 by means of the following circuit: battery, through the winding of magnet 310, lower right-hand, contact of sequence switch spring 305 (5), contact and left-hand armature of relay 412, front contact and armature of relay 413, armature and contact of relay 419 to subbattery and ground.

At the time the operator sets up the numerical record on the keys of rows 500, 501, 502 and 503, she also depresses the start key 520 which closes a circuit from subbattery through the left-hand contacts of said key, conductor 533, winding of relay 515, conductor 534, conductor 441, and thence to battery as above traced at the left-hand armature and contact of relay 303. Relay 515 becomes energized and closes a locking circuit for itself independently of start key 520. This locking circuit may be traced from subbattery through the lower contacts of sequence switch spring 311 (1+6), conductor 361, left-hand armature and contact and winding of relay 315, and thence to battery, as above described. Relay 515, at its right-hand armature and contact, completes a circuit for relay 514. Relay 514 closes a circuit from subbattery through its left-hand armature and contact, and thence over a plurality of parallel branches, one of which leads through the right-hand armature and contact of relay 509, winding of the magnet of register 504; another through the right-hand armature and contact of relay 510, winding of the magnet of register 505; another through the right-hand armature and contact of relay 511, winding of the magnet of register 506; another through the right-hand armature and contact of relay 512, winding of the magnet of register 507; and the last through the armature and back contact of relay 513, winding of the magnet of register 508, which branches then lead respectively by way of conductors 535, 536, 537, 538 and 539, and the contacts of sequence switch springs 323 and 322, closed in position 2+6, to battery and ground. The registers 504, 505, 506, 507 and 508 are energized in these circuits and commence to rotate in search of the positions determined by the particular

numerical keys depressed on the operator's keyboard. When register 504 reaches position 9 a circuit is closed from subbattery through the contacts of key 516, upper right-hand contact of spring 521 (9), winding of relay 509, lower left-hand contact of sequence switch spring 328, winding of relay 303, upper contact of sequence switch spring 333 (1), left-hand armature and contact of relay 303 to battery and ground. When register 505 reaches position 7 a circuit is closed from subbattery through the contacts of key 517, lower left-hand contact of spring 522 (7), winding of relay 510, lower right-hand contact of sequence switch spring 328, and thence to battery and ground. When register 506 arrives in position 4 a circuit is closed from subbattery through the contacts of key 518, lower right-hand contact of spring 523, winding of relay 511, upper right-hand contact of sequence switch spring 327, and thence to battery and ground. As soon as register 507 advances to position 4 a circuit is completed from subbattery through the contacts of key 519, lower right-hand contact of spring 524 (4), winding of relay 512, lower right-hand contact of sequence switch spring 327 to battery and ground. Similarly, when the stations register 508 reaches position 0, a circuit is established from subbattery through the normal contacts of key 532, middle contacts of start key 520, upper right-hand contact of spring 525 (0), winding of relay 513, lower right-hand contact of sequence switch spring 326 (1) to battery and ground. The several relays 509, 510, 511, 512 and 513 become energized in the circuits above traced and open the driving circuits for the corresponding registers, causing them to come to rest in the proper positions for recording the numerical designation of the called subscriber's line. The actuation of the several relays 509, 510, 511, etc. completes a circuit from subbattery through the armature and contact of relay 514, armature and front contact of relay 513, and thence through the contacts and left-hand armatures of relays 512, 511, 510 and 509 in series, lower left-hand contact of sequence switch spring 305 (6) winding of magnet of sequence switch 310 to battery for driving said sequence switch out of position 6 and into position 7.

Release of the operator's keys.

When the cord finder sequence switch 310 arrives in position 7 circuits are closed for the key release magnets which become energized and permit the actuated keys to restore to their normal positions. These circuits lead from subbattery through the windings of magnets 420, 421, 422, 423 and 424, respectively, the upper and lower contacts of sequence switch spring 304 to bat-

tery and ground. As soon as the last one of the depressed keys is released all of the branches of the circuit, previously traced through the winding of relay 303, are opened and this relay becomes deenergized. Relay 303 closes a circuit from subbattery through its right-hand armature and contact, upper left-hand contact of sequence switch spring 306 (7), winding of the magnet of sequence switch 310 to battery, driving said sequence switch out of position 7 and into position 8. In position 8 of the cord finder sequence switch 310, the allotter switch 320 is advanced out of position 1 and operates to select and allot the next idle register sender for use in a manner to be described hereinafter. As sequence switch 310 passes out of position 7½, the contacts of spring 304 are opened and the key release magnets 420, 421, 422, etc. become deenergized ready to hold other actuated keys in their depressed position.

Operation of district selector switch.

As soon as the class and district brush registers have been positioned, district brush selection is proceeded with without awaiting the setting of the subsequent registers. It will be recalled that following the setting of registers 404 and 405, the cord finder sequence switch 310 moved out of position 3 and into position 4. In position 4 of this sequence switch a circuit is completed from battery through the winding of the magnet of the sender sequence switch 610, lower right-hand contact of sequence switch spring 605 (1), upper right-hand contact of sequence switch spring 313 (4+6) to subbattery and ground. Sequence switch 610 moves into position 2 where the fundamental circuit is closed for controlling district brush selection. This circuit may be traced from battery through the winding of relay 120, Fig. 1, lower left-hand contact of sequence switch spring 142 (2), lower right-hand contact of sequence switch spring 142 (2+5), conductor 354, terminal 348, brush 342, lower left-hand contact of sequence switch spring 611 (2), contact and outer armature of the 0' counting relay 625, winding of stepping relay 600, outer left-hand armature and back contact of relay 601, upper contact of sequence switch spring 606 (2), resistances 626 and 627, upper left-hand contact of sequence switch spring 313 (3+8) to subbattery and ground. Relay 120 operates and closes a locking circuit for itself from battery through its winding and contact and right-hand armature, lower right-hand contact of sequence switch spring 144 (2+5), lower right-hand contact of sequence switch spring 142 (2+5), thence to ground as above traced. Relay 120 completes a circuit from battery through the winding of sequence switch magnet 110,

lower left-hand contact of sequence switch spring 128 (2), front contact and left-hand armature of relay 120, back contact and right-hand armature of relay 113, lower right-hand contact of sequence switch spring 135 (2+18) to subbattery and ground. Sequence switch 110 moves from position 2 to position 3. In position 3 a circuit is closed for the updrive power magnet 147, traceable from battery through the winding of said magnet, lower right-hand contact of sequence switch spring 128 (3), front contact and left-hand armature of relay 120, and thence to subbattery and ground at sequence switch spring 135. The magnet 147 causes the upward movement of the brush shaft 150 to select the proper set of brushes to be used in extending the calling line.

The stepping relay 600, which also energizes in the fundamental circuit, completes a circuit from subbattery through its contact and armature, conductor 628, upper contact of sequence switch spring 321 (3+8), upper right-hand contact of sequence switch spring 623 (2), contact of spring 433 of the class register, closed in position 2, lower right-hand contact of spring 436 of the district brush register 405, closed in position 4, conductor 442, armature and back contact of the No. 4' counting relay 631 winding of No. 4 counting relay 632 to battery. Relay 632 energizes in this circuit and prepares a circuit from battery through its winding, the winding of relay 631, contact and armature of relay 632, right-hand contact of sequence switch spring 620 (2) to subbattery. Relay 631, however, being shunted out by the direct path to subbattery at the armature and contact of relay 600 does not become energized at this time. As soon as the brush shaft 150 of the district selector switch in its upward movement approaches the first brush tripping position, commutator brush 158 engages the first metallic segment of commutator 161 and a circuit is closed as follows for relay 120 in shunt of the stepping relay 600 in the fundamental circuit: battery, through the winding and contact and right-hand armature of relay 120, lower right-hand contact of sequence switch spring 144, upper right-hand contact of sequence switch spring 142 (2½+3), commutator 161, brush 158, upper contact of sequence switch spring 135 (8+6) to subbattery. The stepping relay 600, being shunted out, deenergizes and removes the shunt from around the winding of the No. 4' counting relay 631. Relay 631 thereupon energizes in series with relay 632. When brush 158 reaches the next insulating segment of commutator 161, the shunt is removed and the stepping relay 600 again energizes and a circuit is completed from subbattery through its armature and contact, conduc-

tor 628, and thence, as above traced, to the conductor 442, armature and front contact of relay 631, armature and back contact of the No. 3' counting relay 629, winding of relay 630 to battery and ground. Relay 630 energizes and completes a series circuit for itself and relay 629, which latter relay, however, does not energize due to the fact it is shunted out. When the commutator brush 158 engages the next metallic segment of the commutator 161, relay 600 is shunted, deenergizes and removes the shunt from around the winding of relay 629, which relay thereupon operates in series with relay 630. In like manner, for each brush tripping position to which the brush shaft 150 is driven, a pair of counting relays are energized and locked up until finally the 0 and 0' counting relays 634 and 625, respectively are energized. Relay 625, at its outer armature and contact, opens the fundamental circuit to prepare for the release of relay 120. Relay 625 also completes a circuit from battery through the winding of sequence switch magnet 610, contact and inner armature of relay 625, left-hand contact of sequence switch spring 620 (2) to subbattery and ground for driving sequence switch 610 out of position 2 and into position 3. As sequence switch 610 leaves position 2 the contacts of spring 620 are opened and the energized counting relays are permitted to release.

As soon, following the opening of the fundamental circuit by the 0' counting relay, as the brush 158 engages the next insulating segment of commutator 161, the holding circuit of relay 120 is opened and this relay retracts its armatures to open the circuit of the power magnet 147. The switch shaft 150, therefore, comes to rest in the position for tripping the proper set of brushes. Relay 120 completes a circuit from battery through the winding of sequence switch magnet 110, lower right-hand contact of sequence switch spring 130 (3), back contact and left-hand armature of relay 120 to subbattery and ground at sequence switch spring 135, driving sequence switch 110 out of position 3 and into position 4. In position 4 a circuit is completed from battery through the winding of trip magnet 146, upper left-hand contact of sequence switch spring 134 to subbattery and ground. The trip magnet 146 energizes and rotates the trip spindle 149 such that the selected set of brushes will be tripped on the next movement of the shaft 150.

It will be recalled that the cord finder sequence switch 310 is advanced from position 4 into position 5 only after the district group register 406 has reached its set position. If, therefore, sequence switch 310 has reached position 5, indicating that the district group register has been set at the 130

time the sender sequence switch 610 reaches position 3, said sender sequence switch is driven immediately into position 4 by means of the following circuit: battery, through 5 the winding of sequence switch magnet 610, lower left-hand contact of sequence switch spring 615 (2+18), upper left-hand contact of sequence switch spring 615 (3), left-hand contact of sequence switch spring 325 10 (5+15) to subbattery and ground. With the sequence switch 110 in position 4 and sequence switch 610 in position 4, the fundamental circuit is again closed, as above traced, for controlling group selection at 15 the district switch. The relay 120, which energies in the fundamental circuit, locks up in the manner above described and also completes a circuit from battery through the winding of sequence switch magnet 110, 20 lower left-hand contact of sequence switch spring 128 (4), front contact and left-hand armature of relay 120 to subbattery and ground at sequence switch spring 135. Sequence switch 110 moves from position 4 25 into position 5. In this position the circuit of the power magnet 147 is again closed, as above traced, and the brush shaft 150 is moved upwardly to advance the tripped set of brushes 151, 152 and 153 over the terminals of the contact bank to select the proper group thereof. The stepping relay 600, which also operates in the fundamental circuit, completes a circuit from subbattery 30 through its contact and armature conductor 628, upper contact of sequence switch spring 321 (3+8), lower right-hand contact of sequence switch spring 623 (4), contact of spring 434 (1+3), upper right-hand contact of spring 438 (1) of the district group 35 register 406, conductor 445, armature and back contact of counting relay 635, winding of relay 636 to battery. Relay 636 operates and closes a series circuit for itself and relay 635. Relay 635, however, remains de- 40 energized since its winding is shunted out by the stepping relay 600.

When the brush shaft 150 approaches the first group selecting position, commutator brush 159 encounters the first metallic segment of commutator 162 and the following circuit is closed for relay 120 in shunt of the stepping relay 600 in the fundamental circuit: battery, through the winding and contact and right-hand armature of relay 120, lower right-hand contact of sequence switch spring 144 (2+5), upper left-hand contact of sequence switch spring 142 (4½+5), commutator 162, brush 159 to subbattery through the upper contact of sequence switch spring 135. Relay 120 remains energized but the stepping relay 600, being shunted, releases its armature and opens the shunt circuit around the No. 1' counting relay 635. Relay 635 thereupon 50 operates in series with relay 636, the circuit

being completed at the right-hand contact of sequence switch spring 620 (4). When the district selector switch reaches the next group position and the stepping relay 600 is again shunted, the 0 and 0' counting relays 70 are energized in a similar manner and the fundamental circuit is opened at the outer armature and contact of the 0' counting relay to terminate the movement of the switch. The 0' counting relay 625, at its 75 inner armature and contact, completes the circuit above traced for driving the sender sequence switch out of position 4 and into position 5. On leaving position 4 the sender sequence switch opens its contact 620 to 80 allow the energized counting relays to release.

As soon, after the fundamental circuit is opened at the sender, as the brush 159 engages the next insulating segment of commutator 162, relay 120 becomes deenergized and, opening the circuit of the power magnet 147, causes the brush shaft 150 to come to rest in operative relation with the proper group of trunks. Relay 120, furthermore, 85 completes a circuit from battery through the winding of sequence switch magnet 110, lower right-hand contact of sequence switch spring 130 (5), back contact and left-hand armature of relay 120 to subbattery at sequence switch spring 135. Sequence switch 110 is advanced from position 5 into position 6.

In position 6 of the district sequence switch 110 a circuit is closed from battery 100 through the right-hand winding of test relay 114, lower left-hand contact of sequence switch spring 143 (6+7), lower right-hand contact of said spring (2+6) to subbattery and ground. Relay 114 energizes in this circuit and closes the following locking circuit for itself, provided the first trunk in the group, upon the terminals of which the brushes 151, 152 and 153 are now standing, 105 is busy: battery, through the left-hand winding and front contact and left-hand armature of relay 114, test brush 153 to subbattery connected to the test terminal of the busy trunk. Relay 114 completes a circuit 110 from battery through the winding of sequence switch magnet 110, lower left-hand contact of sequence switch spring 128 (6), front contact and right-hand armature of relay 114, back contact and right-hand armature of relay 113, lower right-hand contact 115 of sequence switch spring 135 (2+18) to subbattery. Sequence switch 110 moves out of position 6 and into position 7. In position 7 a circuit is again closed for the updrive power magnet 147, traceable from battery 120 through the winding of said magnet, lower right-hand contact of sequence switch spring 128 (7), front contact and right-hand armature of relay 114 to subbattery at sequence switch spring 135. The brushes 151, 152

125

130

and 153 are now driven over the terminals of the selected group of trunks in search of an idle one therein. When the first idle trunk is reached the holding circuit of test 5 relay 114 is opened but this relay remains energized in the following circuit for an instant longer to permit the brushes to be accurately centered on the terminals of the 10 idle trunk: battery, through the right-hand winding of relay 114, lower left-hand contact of sequence switch spring 143 (6+7), upper right-hand contact of said spring (7), commutator 160, brush 157, upper contact of spring 128 (7), the right-hand armature 15 and front contact of relay 114 to subbattery at the lower contact of sequence switch spring 135. The brushes being accurately 20 centered the above traced circuit is opened and relay 114 releases to open the circuit of the updrive power magnet 147. Relay 114, in addition, completes a circuit from battery through the winding of sequence switch magnet 110, lower right-hand contact of sequence switch spring 138, back contact 25 and right-hand armature of relay 114 to subbattery at the sequence switch spring 135, driving sequence switch 110 out of position 7 and into position 8.

It will be recalled that the cord finder sequence switch 310 does not pass into position 6 until the office and brush group registers 407 and 408 have been positioned. Assuming these registers have been set at the 30 time the district sequence switch 110 reaches position 8; a circuit is completed as follows for moving the sender sequence switch 610 out of position 5 and into position 6: battery, through the winding of sequence switch magnet 610, upper right-hand contact of sequence switch spring 605 (5), upper left-hand contact of sequence switch spring 314 (6+8), brush 344, terminal 350, conductor 356, lower left-hand contact of sequence switch spring 134 (8) to subbattery and ground. When the sender sequence switch 45 advances to position 6 a circuit is closed from battery through the winding of relay 120, lower left-hand contact of sequence switch spring 142 (8), lower left-hand contact of sequence switch spring 144 (8), conductor 355, terminal 349, brush 343, left-hand contact of sequence switch spring 315 (5+8), upper left-hand contact of sequence switch spring 617 (6+11), lower right-hand contact of 50 said spring (6+8) to subbattery and ground. Relay 120 is energized and closes a circuit from battery through the winding of sequence switch magnet 110, lower left-hand contact of sequence switch spring 128 (8), front contact and left-hand armature of relay 120 to subbattery at sequence switch spring 135. Sequence switch 110 advances from position 8 into position 9. While the sequence switch 110 is passing 65 through position 8 into position 9, relay 120

is held energized, first by means of a circuit from battery through the winding and contact and right-hand armature of said relay, lower right-hand contact of sequence switch spring 137 (8+8½), upper left-hand contact of said spring (2+16½), back contact and left-hand armature of relay 113 to subbattery. As sequence switch 110 reaches position 8½, the following circuit is closed prior to the opening of the circuit last traced and serves to hold the relay 120 energized after the sequence switch moves into position 9: battery, through the winding and contact and right-hand armature of relay 120, upper right-hand contact of sequence switch spring 145 (8¾+9), upper left-hand contact of said spring (8+11), conductor 355, terminal 349, brush 343, left-hand contact of sequence switch spring 315 (5+8), upper left-hand contact of sequence switch spring 617 (6+11), lower right-hand contact of said spring (6+8) to subbattery and ground. The relay 120 is maintained energized in this circuit until office selection has been completed and the sender sequence switch 610 advances out of position 8. It may be noted that springs 137 and 145 are cut so as to have overlapping closures between positions 8 and 9. Accordingly, the lower right contact of spring 137 does not open in point of time until slightly after the upper right contact of spring 145 closes.

Operation of office selector switch.

The fundamental circuit is now extended from the sender through to the office selector switch in Fig. 7 ready for controlling the office brush selection. This circuit may be traced from battery through the right-hand winding of relay 700, lower left-hand contact of sequence switch spring 711 (1), lower right-hand contact of said spring (1+4), terminal 154, brush 151, upper right-hand contact of sequence switch spring 144 (9), lower right-hand contact of sequence switch spring 142 (9+11), conductor 354, terminal 348, brush 342, left-hand contact of sequence switch spring 611 (6), contact and outer armature of relay 625, winding of stepping relay 600, outer left-hand armature and back contact of relay 601, lower contact of sequence switch spring 606 (6), resistances 637 and 627, upper left-hand contact of sequence switch spring 313 (3+8) to subbattery and ground. Relay 700 becomes energized and completes a locking circuit for itself traceable from battery through its right-hand winding and front contact and inner right-hand armature, lower right-hand contact of sequence switch spring 716 (1+10), lower right-hand contact of sequence switch spring 711 (1+4), and thence to subbattery as described. Relay 700 also completes a circuit from subbattery through its left-hand armature and front contact, upper left-

hand contact of sequence switch spring 707 (1), winding of relay 701 to battery. Relay 701 operates and locks up in a circuit through its front contact and left-hand armature, test terminal 156, brush 153, left-hand armature and back contact of relay 114, upper right-hand contact of sequence switch spring 137 ($6\frac{1}{2}+16\frac{1}{2}$), upper left-hand contact of sequence switch spring 137 (2+16 $\frac{1}{2}$) to subbattery at the left-hand armature and back contact of relay 113. This circuit from subbattery to the test terminal 156 also serves to render the selected trunk busy to other district selector switches. Relay 701 operates and completes a circuit from subbattery through its right-hand armature and front contact, lower left-hand contact 748 (1), winding of sequence switch magnet 710 to battery for driving said sequence switch out of position 1 and into position 2: In position 2 a circuit is closed from battery through the winding of the up-drive power magnet 718, lower right-hand contact of sequence switch spring 707 (2), front contact and left-hand armature of relay 700 to subbattery. Magnet 718 causes the brush shaft 720 to move upwardly for the purpose of selecting the proper set of brushes.

The stepping relay 600, which also energizes in the fundamental circuit, completes a circuit from subbattery through its contact and armature, conductor 628, upper contact of sequence switch spring 321 (3+8), upper left-hand contact of sequence switch spring 623 (6), upper contact of spring 432 (1+3), lower right-hand contact of spring 439 (4), conductor 442, armature and back contact of relay 631, winding of relay 632 to battery. Relay 632 operates and prepares a series circuit for itself and relay 631, as hereinbefore explained. Relay 631 remains shunted out until the stepping relay 600 releases.

When the brush shaft 720 approaches its first tripping position, commutator brush 742 encounters a metallic segment of commutator 745 and a holding circuit is closed for relay 700 in shunt of the stepping relay 600 in the fundamental circuit. This holding circuit may be traced from battery through the right-hand winding and front contact and inner right-hand armature of relay 700, lower right-hand contact of sequence switch spring 716 (1+10), upper left-hand contact of sequence switch spring 711 (13 $\frac{1}{4}$ +2), commutator 745, brush 742, left-hand contact of sequence switch spring 702 (12+5) to subbattery and ground. The stepping relay 600, being shunted out, releases and removes the short circuit from around the winding of relay 631, permitting this relay to operate and lock up in series with relay 632. When commutator brush 742 encounters the next insulating segment, the stepping relay 600

reenergizes and completes the circuit above traced to conductor 442, armature and front contact of relay 631, armature and back contact of relay 629, winding of the next counting relay 630 to battery. In a similar manner to that already described, the relay 630 operates and prepares a series circuit for itself and relay 629. This method of operation proceeds, a pair of counting relays being energized and locked up for each tripping position passed over by the brush shaft 720, until the 0 and 0' counting relays are energized. The 0' counting relay 625, on operating, opens the fundamental circuit at its outer armature, and at its inner armature completes a circuit from battery through the winding of sequence switch magnet 610, contact and inner armature of said relay, left-hand contact of sequence switch spring 620 (6) to subbattery and ground. Sequence switch magnet 610 advances from position 6 into position 8. On leaving position 6 the contact of sequence switch spring 620 is opened to cause the release of the energized counting relays.

As soon following the opening of the fundamental circuit by the 0' counting relay as the commutator brush 742 engages the next insulating segment of commutator 745, the holding circuit of relay 700 is opened and this relay releases its armatures to sever the circuit of the power magnet 718, the brush shaft 720 thereupon comes to rest in the required position for tripping the proper set of brushes 721, 722 and 723. Relay 700 at the same time closes a circuit from subbattery through its left-hand armature and back contact, upper left-hand contact of sequence switch spring 748 (2), winding of sequence switch magnet 710 to battery, moving said sequence switch out of position 2 and into position 3.

With sequence switch 710 in position 3 and the sender sequence switch 610 in position 8, the fundamental circuit, hereinbefore traced, is again established preparatory to controlling the group selecting movement of the office selector. Relay 700, on energizing in the fundamental circuit, closes a circuit from subbattery through its left-hand armature and front contact, lower left-hand contact of sequence switch spring 709 (3), winding of sequence switch magnet 710 to battery, driving sequence switch 710 out of position 3 and into position 4. In position 4 the relay 700 remains locked up in the fundamental circuit in the manner above explained. The circuit of the updrive power magnet 718 is now completed through the lower right-hand contact of sequence switch spring 707 (4), and the shaft is driven upwardly in the group selecting movement.

The stepping relay 600, which also energizes in the fundamental circuit completes a circuit from subbattery through its contact

and armature, conductor 628, upper contact of sequence switch spring 321 (3+8), lower left-hand contact of sequence switch spring 628 (8), upper contact of spring 435 (1+3), 5 lower left-hand contact of spring 440 (3), conductor 446, armature and back contact of counting relay 629, winding of counting relay 630 to battery. Relay 630 operates and prepares a series holding circuit for itself 10 and counting relay 629. As the brush shaft 720 approaches the first group selecting position, commutator brush 741 engages the metallic segment of commutator 744 to close the following circuit for relay 700 in shunt 15 of the stepping relay 600 in the fundamental circuit: battery, through the right-hand winding and front contact and inner left-hand armature of relay 700, lower right-hand contact of sequence switch spring 716, 20 upper right-hand contact of sequence switch spring 711 (3 3/4+4), commutator 744, brush 741 to subbattery at the left-hand contact of sequence switch spring 702. Relay 700 remains energized but relay 600, being 25 shunted, releases its armature and opens the short circuit around the winding of the No. 3' counting relay 629. Relay 629 thereupon energizes in series with relay 630. Likewise, for each succeeding group of terminals in 30 the bank passed over by the brushes 721, 722 and 723, the stepping relay 600 is shunted and the counting relays are energized and locked up in succession. When finally the brushes approach the desired group of terminals 35 the 0 and 0' counting relays are operated and the fundamental circuit is opened at the outer armature and contact of the 0' relay 625. Relay 625 at the same time closes the circuit hereinbefore traced for advancing the sender sequence switch out of position 8 and into position 9. On leaving position 8 sequence switch 610 opens at its 40 spring 620 the locking circuit of the counting relays. 45 As soon, after the opening of the fundamental circuit at the sender, as the brush 741 engages the next insulating segment of commutator 744, the holding circuit of relay 700 is opened and this relay retracts its 50 armatures to open the circuit of the updrive power magnets 718, thereby causing the brush shaft 720 to cease its upward movement. Relay 700 also completes a circuit from subbattery through its left-hand armature and back contact, upper left-hand contact of sequence switch spring 748 (4), winding of sequence switch magnet 710 to battery, moving said sequence switch into 55 position 5. 60 In position 5 of sequence switch 710 a circuit is closed from battery through the left-hand winding of relay 700, lower left-hand contact of sequence switch spring 703 (5+8), lower right-hand contact of said 65 spring (3+5 1/4) to subbattery and ground.

Relay 700 operates and closes the following holding circuit for itself, provided the first trunk in the selected group, upon the terminals 724, 725 and 726 of which the brushes 721, 722 and 723 are now standing, is busy: 70 battery, through the right-hand winding and front contact and inner right-hand armature of relay 700, lower right-hand contact of sequence switch spring 716 (1+10), upper left-hand contact of said spring (5+7), 75 brush 723 to subbattery on test terminal 726 of the busy trunk. Relay 700, on operating, completes a circuit from subbattery through its left-hand armature and front contact, lower left-hand contact of sequence switch spring 709 (5), winding of sequence switch magnet 710 to battery for moving the 80 said sequence switch out of position 5 and into position 6. In position 6 a circuit is closed, as above traced, for the updrive power magnet 718 and the brush shaft 720 is moved upward to drive the brushes over the terminals of the bank to search for an 85 idle trunk. When an idle trunk is reached no subbattery potential is existing on the 90 test terminal thereof and relay 700 is de-energized and closes a circuit as follows for driving sequence switch 710 out of position 6 and into position 8: battery, through the 95 winding of the magnet of said sequence switch, upper left-hand contact of sequence switch spring 748 (6), back contact and left-hand armature of relay 700 to subbattery and ground. 100

Following the office group selection the sender sequence switch 610 moves out of position 8, as above described, and in so doing opens, at its spring 617, the circuit which has been maintaining the energization of relay 120. Relay 120 retracts its armatures and completes a circuit from battery through the winding of the magnet of sequence switch 110, lower right-hand contact of sequence switch spring 130, back contact and left-hand armature of relay 120 to subbattery at the sequence switch spring 135. Sequence switch 110 advances out of position 9, through position 10 and into position 11. 115

At this stage in the operation of the system a test is made by the sender to determine whether the office selector switch has succeeded in finding an idle trunk in the chosen group, or whether it has gone to the overflow position as a result of all trunks in the group being simultaneously busy. The first assumption is that the switch succeeded in finding an idle trunk and that the sequence switch 710 moves from position 6 into position 8, as just explained. Referring to the sender circuits, it will be noted that a circuit is closed as follows when the sender sequence switch 610 moves into position 9, which position it assumes following the completion of the office group selection and with 120 125 130

- the sequence switch 710 in position 8: battery, through the left-hand winding of marginal relay 603, winding of sensitive relay 602, outer armature and contact of relay 604, 5 lower left-hand contact of sequence switch spring 617 (9+10), upper left-hand contact of said spring (6+11), left-hand contact of sequence switch spring 315 (5+8), brush 343, terminal 349, conductor 355, upper left- 10 hand contact of sequence switch spring 145 (8+11), lower right-hand contact of sequence switch spring 145 (11+16), brush 152, terminal 155, lower left-hand contact of sequence switch spring 714 (8+9), re- 15 sistance 715 to subbattery and ground. Relay 602 operates in this circuit but relay 603, being marginal, does not receive sufficient current in series with resistance 715 to attract its armatures. Relay 602, on operat- 20 ing, closes a circuit from subbattery through its left-hand armature and front contact, lower left-hand contact of sequence switch spring 612 (9), winding of sequence switch magnet 610 to battery for driving sequence 25 switch 610 out of position 9 and into position 10. Simultaneously with the closure of this circuit relay 602 also completes the following circuit which is maintained from position 9 to position 9½ of sequence switch 30 610, for causing the advance of the office sequence switch 710: battery, through the right-hand winding of relay 700, lower left-hand contact of sequence switch spring 711 (8), lower right-hand contact of said spring 35 (8+9), terminal 154, brush 151, upper right-hand contact of sequence switch spring 144 (11+16), lower right-hand contact of sequence switch spring 142 (9+11), conductor 354, terminal 348, brush 342, lower right- 40 hand contact of sequence switch spring 611 (9+9½), right-hand armature and contact of relay 602, resistances 637 and 627, upper left-hand contact of sequence switch spring 313 (3+8) to subbattery. Relay 700 be- 45 comes energized and closes a circuit from battery through the winding of sequence switch 710, lower left-hand contact of sequence switch spring 709 (8), front contact and left-hand armature of relay 700 to sub- 50 battery, driving sequence switch 710 out of position 8 and into position 9. When, an instant later, the sequence switch 610 leaves position 9½, relay 700 becomes deenergized and closes a circuit from battery through the winding of sequence switch magnet 710, upper left-hand contact of sequence switch spring 748 (9), and back contact and left- 55 hand armature of relay 700 to subbattery for moving sequence switch 710 out of position 60 9 and into position 10. As sequence switch 710 leaves position 9 the above traced circuit for the sensitive relay 602 is opened at the lower left-hand contact of sequence switch spring 714. Relay 602, on releasing 65 its armatures, closes a circuit from battery through the winding of sequence switch mag- 70 net 610, lower left-hand contact of sequence switch spring 605, back contact and left- hand armature of relay 602 to subbattery, driving sequence switch 610 into posi- 75 tion 11.
- The district and office selector switches have been positioned and the sender is now in condition to control the selective movements of the incoming and final switches, provided the operator has completed the setting up of the numerical record on her keyboard at this time. It is not thought necessary to show the circuits in detail for the incoming and final switches, inasmuch as 80 they have no direct bearing on the subject matter of the invention claimed. Accordingly, these switches have been diagrammatically illustrated as shown in Fig. 7. Provided the numerical keys have all been depressed, the circuit, hereinbefore traced, which leads through the contacts and armatures of relays 509, 510, 511, etc. has been closed to advance the cord-finder sequence switch out of position 6 and into position 7, 85 from whence it is driven into position 8 following the release of the operator's keys, as already explained. With sequence switch 310 in position 8 the sender sequence switch is immediately driven out of position 11 and into position 12 by means of a circuit from battery through the winding of said sequence switch, upper left-hand contact of sequence switch spring 612 (11), left-hand contacts of sequence switch spring 317 (8), 90 conductor 362, thence to conductor 362, Fig. 4, lower left-hand contact of spring 431 (2) to subbattery. 95
- For clearness, the conductor 362, which leads, as mentioned, from the sequence switch spring 317 in Fig. 3 to spring 431 in Fig. 4, has been omitted and the convention of the circles containing corresponding Roman numerals adopted in its stead. This 100 same convention is also used, as will appear hereinafter, in substitution of certain other conductors which have been omitted from the drawing to avoid unnecessary confusion. The spring 431 in Fig. 4 is a part 105 of the class register 404, which, for the particular class of calls being considered, is assumed to be in position 2. 110
- Consequently, sequence switch 610 is driven into position 12. In position 12 of sequence switch 610 a circuit is closed from battery through the windings of counting relays 634 and 625 in series, lower contacts of sequence switch spring 312 (4+8), upper left-hand contact of sequence switch spring 619 (11+8), upper right-hand contact of 115 said spring (11+16), conductor 633, and thence to conductor 633, Fig. 4, upper left-hand contact of spring 430 (2) to subbattery and ground. Relay 625 completes a circuit 120 from battery through the winding of se- 125 quence switch spring 311 (11+16), upper right-hand contact of said spring (11+16), conductor 633, and thence to conductor 633, Fig. 4, upper left-hand contact of spring 430 (2) to subbattery and ground. Relay 625 completes a circuit 130 from battery through the winding of sequence switch magnet 610, lower left-hand contact of sequence switch spring 605, back contact and left-hand armature of relay 602 to subbattery, driving sequence switch 610 into position 11. 135

quence switch magnet 610, contact and inner armature of relay 625, left-hand contact of sequence switch spring 620 to subbattery. Sequence switch 610 moves from position 12 into position 13. A circuit is now closed from battery through the winding of sequence switch magnet 610, upper left-hand contact of sequence switch spring 612 (13), and thence, as above traced, to subbattery at spring 431 of the class register. Sequence switch 610 moves into position 14 from whence it is immediately driven into position 15 by means of the circuit closed at the inner armature of the counting relay 625. In position 15 the circuit, which leads through the upper left-hand contact of sequence switch spring 612 to subbattery at the spring 431 of the class register, is again closed to drive sequence switch 610 into position 16. From this position it is advanced into position 1 by means of the circuit closed by the 0' counting relay 625. On leaving position 16 the circuit for the relays 634 and 625 is opened and these relays release their armatures.

As sequence switch 610 moves into position 17 a circuit is closed from battery through the winding of the cord finder sequence switch magnet 310, upper contacts of sequence switch spring 616 (17+1), lower left-hand contact of sequence switch spring 313 (8) to subbattery and ground, driving sequence switch 310 out of position 8 and into position 15. When sequence switch 310 reaches position 9 on its way to position 15 a circuit is completed from battery through the winding of sequence switch magnet 610, lower right-hand contact of sequence switch spring 605, upper right-hand contact of sequence switch spring 313 (9+15) to subbattery, advancing the sender sequence switch 610 out of position 1 and into position 2.

Operation of incoming selector switch.

With the sender sequence switch in position 2 of its second revolution and the cord finder sequence switch 310 in position 15, the fundamental circuit is extended to the incoming selector switch, indicated by the brushes 727, 728 and 729, for controlling brush selection. This circuit will lead through the winding of a relay at the incoming switch, similar to relay 700 belonging to the office switch, over terminal 724, brush 721, contact of sequence switch spring 712 (10), thence over the upper side of the fundamental circuit, as already traced, through the terminal 348 of the cord finder switch, brush 342, lower left-hand contact of sequence switch spring 611 (2), contact and outer armature of relay 625, winding of the stepping relay 600, outer armature and back contact of relay 601, lower contact of sequence switch spring 607 (2), winding of relay 609, normal contacts at

the right-hand armature of relay 608, right-hand contact of sequence switch spring 315 (9+15), brush 343, terminal 349, conductor 355, upper left-hand contact of sequence switch spring 145 (8+11), lower right-hand contact of said spring (11+16), brush 152, terminal 155, contact of spring 713 (10), brush 722, terminal 725, and thence to ground in the well-known manner at the incoming selector switch. Power is applied to cause the upward movement of the brush shaft of the incoming selector switch and an intermittent shunt circuit is established for repeatedly shunting down the stepping relay 600 in the fundamental circuit. 80

Relay 600, on first energizing, completes a circuit from subbattery through its contact and armature, conductor 628, lower contact of sequence switch spring 321 (9+15), upper left-hand contact of sequence switch spring 621 (2), upper right-hand contact of spring 526 of the thousands register 504, which, it will be recalled, is standing in position 9, conductor 442, armature and back contact of counting relay 631, winding of counting relay 632 to battery. For each shunting of the relay 600 a pair of counting relays are operated in succession until finally the 0' counting relay 625 is energized to open the fundamental circuit, and also to advance the sender sequence switch 610 out of position 2 and into position 3, as hereinbefore explained. From position 3 the sender sequence switch 610 is immediately driven into position 4 by means of the circuit traced to subbattery at the left-hand contact of sequence switch spring 325 (5+15).

The method of translation employed in systems of this character, whereby the fifth set of brushes of the incoming selector, chosen as above related, has access through final switches to lines having the thousands digit 9, is set forth in detail in the patent to A. E. Lundell, No. 1,403,861, issued January 17, 1922. 110

The fundamental circuit is again established and the tripped set of brushes at the incoming switch is driven upwardly to select the proper group of terminals. The stepping relay 600, which energizes in the fundamental circuit, now completes a circuit from subbattery through its contact and armature, thence over conductor 628 to the upper right-hand contact of sequence switch spring 621 (4), upper contact of spring 527 (9), upper contact of spring 529 of the hundreds register 505 closed in position 7, conductor 446, armature and back contact of relay 629, winding of relay 630 to battery. As the incoming switch moves from one group selecting position to another, the stepping relay 600 is repeatedly shunted and the counting relays are operated and locked up in succession. When 120

the 0' counting relay 625 operates it opens circuit is established and the stepping relay 600 energizes to complete a circuit from the fundamental circuit and also closes the subbattery through its contact and armature, over conductor 628 to the upper contact of sequence switch spring 622 (12), 70 lower right-hand contact of spring 531 of register 507, closed in position 4, conductor 442, armature and back contact of relay 631, winding of relay 632 to battery. When the brushes 733, 734 and 735 have been driven 75 to the terminals 736, 737 and 738 of the called subscriber's line 740, the 0' counting relay 625 operates, opens the fundamental circuit, and also closes a circuit for driving the sender sequence switch 610 out of position 12 and into position 13. The relay 609, which is included in the fundamental circuit during incoming brush, incoming group, final brush, and final group selections, is polarized and normally receives 80 current in the opposite direction from that required to cause its operation.

An idle final switch having been selected, the fundamental circuit is again established 20 for controlling final brush selection and the stepping relay 600 is energized. Relay 600 completes a circuit from subbattery through its contact and armature, conductor 628, lower contact of spring 321 (9+15), lower 25 right-hand contact of sequence switch spring 621 (6), lower left-hand contact of spring 528 of the hundreds register 505 closed in position 7, conductor 447, armature and back contact of relay 638, winding of relay 30 639 to battery. For each brush tripping position passed over by the final selector switch, an additional pair of counting relays are energized and locked up until finally the proper position has been reached, 35 at which time 0' counting relay 625 operates to open the fundamental circuit and also to drive the sender sequence switch out of position 6 and into position 8. The fundamental circuit is now closed for controlling 40 final tens selection, the brush shaft is moved upwardly, and the stepping relay 600 in the fundamental circuit is energized to complete a circuit from subbattery through its contact and armature, thence over conductor 628 to the lower left-hand contact of sequence switch spring 621 (8), lower right-hand contact of spring 530 of the tens register 506, closed in position 4, conductor 442, armature and back contact 45 of relay 631, winding of relay 632 to battery. When the 0' counting relay 625 is finally operated it opens the fundamental circuit and closes a circuit for driving the sender sequence switch out of position 8 and into position 9. In this position a circuit 55 is completed from battery through the winding of sequence switch magnet 610, upper left-hand contact of sequence switch spring 605 (9+11), lower right-hand contact of sequence switch spring 313 (9+15) to subbattery and ground, driving said sequence switch out of position 9, through positions 60 10 and 11, and into position 12.

Units selection is now made at the final 65 switch for which purpose the fundamental

Inasmuch as the call under consideration is one wherein no stations impulses are required, the class register has its lower left-hand contact 430 closed in position 2 and the district sequence switch 110 is consequently advanced out of position 11 immediately that final units selection has finished and the sender sequence switch moves into 95 position 13. The circuit for driving sequence switch 110 out of position 11 may be traced from battery through the winding of the magnet of said sequence switch, upper right-hand contact of sequence switch spring 136 (11+17), lower left-hand contact of said spring (11), conductor 356, terminal 350, brush 344, upper left-hand contact of sequence switch spring 618 (13), lower contacts of sequence switch spring 319 (9+15), conductor 363, thence to conductor 363, Fig. 4, lower left-hand contact of spring 430 (2) to subbattery and ground. In position 12 of sequence switch 110 a circuit is closed from battery through the magnet of said sequence switch, upper left-hand contact 138 (12+13), back contact and left-hand armature of relay 112, upper right-hand contact of sequence switch spring 134 (2+13) to subbattery for moving sequence 115 switch 110 into position 14.

Disconnection of operator's telephone set and release of the register sender.

As sequence switch 110 leaves position 112 it opens at the lower left-hand contact of sequence switch spring 137 the circuit which up to this time has been maintaining the energization of relay 300. Relay 300, on deenergizing, completes a circuit from battery through the winding of sequence switch magnet 310, upper left-hand contact of sequence switch spring 307 (8+16), back contact and right-hand armature of relay 300 to subbattery and ground, driving sequence 130

switch 310 out of position 15 and into position 17. In position 17 a circuit is closed from battery through the winding of relay 601, lower right-hand contact of sequence 5 switch spring 308 (17), upper left-hand contact of said spring (1 $\frac{1}{2}$ +17), back contact and right-hand armature of relay 300 to subbattery and ground. Relay 601 closes a circuit from battery through the winding 10 of sequence switch magnet 610, lower left-hand contact of sequence switch spring 615 (2+18), front contact and outer right-hand armature of relay 601 to subbattery, moving said sequence switch from position 13 15 into position 1.

When sequence switch 610 reaches position 1 a circuit is closed from battery through the winding of relay 207, Fig. 2, conductor 217, back contact and left-hand 20 armature of relay 302, upper right-hand contact of sequence switch spring 615 (1), front contact and outer right-hand armature of relay 601 to subbattery. Relay 207 operates in this circuit and opens, at its 25 left-hand armature and contact, the series circuit through the windings of relays 206, 202 and 203. Relays 202 and 203 become deenergized. Relay 203, by releasing its armatures, disconnects the operator's telephone set 210 from the conductors 105 and 106 of the cord circuit, thereby causing her talking equipment to be listened out. Relay 203, at its normal contacts which are 30 of a make and break character, reestablishes the connection from the calling subscriber's line through to the left-hand windings of the repeating coil 117, and relay 115 remains energized to shunt the supervisory lamp 131. Since the plug 104 is still in the 35 jack 103, relays 109 and 200 remain energized, but relay 202 cannot be reenergized to again cause the energization of relay 203, due to the fact that the original operating 40 circuit of relay 202 is now opened at the back contact and left-hand armature of relay 201, this latter relay remaining locked up as long as relay 109 is energized. At the 45 same time that relay 207 operates under the control of the register sender to bring about a disconnection of the operator's telephone set, it closes a circuit from subbattery through its right-hand armature and contact, conductor 218, normal contacts at the 50 right-hand armature of relay 302, winding of said relay, lower right-hand contact of sequence switch spring 322 (2+17) to battery. Relay 302 becomes energized and locks in a circuit closed directly to subbattery through its front contact and right-hand armature. 55

Relay 302 now closes a circuit for the release of the cord finder switch 340 to disassociate the register sender from the cord circuit at the operator's position. This circuit 60 may be traced from battery through

the winding of the downdrive power magnet 337, front contact and left-hand armature of relay 302, upper right-hand contact of sequence switch spring 615 (1), front contact and right-hand armature of relay 601 to subbattery. Magnet 337 causes the restoration of the brush shaft 340, which, on reaching its normal position, closes a circuit from battery through the winding of sequence switch magnet 310, upper left-hand contact of sequence switch spring 305 (8+17), normal segment 341, brush 339 to subbattery. Sequence switch 310 moves from position 17 into position 18, where it awaits allotment by the allotter switch 320. 70 When sequence switch 310 leaves position 18 it opens, at the lower right-hand contact of sequence switch spring 308, the circuit of relay 601. Relay 601 thereupon retracts its armatures. Sequence switch 310, on 75 passing out of position 17, also opens the circuit of relay 302, permitting this relay to become deenergized. The register sender has now been fully restored to its normal 80 position and may be again allotted for use in connection with subsequent calls. It will be noted that when the district sequence switch 110 moved out of position 11, following the completion of units selection, the circuit of lamp 125 is opened and this 85 lamp extinguishes, thereby advising the operator that sender has finished the control of the selective switches. 90

Called subscriber responds.

100

When the connection has been extended through to the called line a test is made thereof, and on finding the line idle ringing current is applied from the incoming selector switch in the well-known manner to 105 operate the signal bell at the substation. In responding to the call by removing his receiver from the switch hook, the called subscriber causes the closure of a circuit in the well-known manner, which may be traced 110 from battery through the lower right-hand winding of repeating coil 117, winding of relay 116, lower left-hand contact of sequence switch spring 145 (12+16), lower right-hand contact of said spring (11+16), 115 brush 152, terminal 155, thence over the ring side of the talking circuit through a closed loop of one of the switches diagrammatically illustrated in Fig. 7, returning over the tip side of the talking circuit to terminal 154, brush 151, upper right-hand contact of sequence switch spring 144 (11+16), upper left-hand contact of said spring (12+16), conductor 169, normal contacts of relay 205, conductor 168, 120 upper right-hand winding of repeating coil 117 to ground. The supervisory relay 113 operates in this circuit and closes a circuit from battery through the winding of sequence switch magnet 110, conductor 167, 125

130

left-hand armature and back contact of relay 202, upper left-hand contact of sequence switch spring 129 (14), armature and contact of sequence switch spring 135 to tact of relay 113 to subbattery and ground. Relay 113 also completes a circuit 5 driving sequence switch 110 out of position 14 and into the talking position, 16. It will be noted that while sequence switch 110 is in position 14 during which time ringing current (11+17), upper left-hand contact of said spring (12+18), front contact and left-hand 10 circuit is closed from subbattery through armature of relay 113 to subbattery, driving the right-hand armature and contact of relay 109, sequence switch magnet 110, upper right-hand contact of sequence switch spring 136 and into position 18. In position 18 a circuit is completed from battery through the left-hand contact of sequence switch spring 127 (14), lower left-hand contact of said 15 spring (12+16) to ground. Lamp 121 is illuminated in this circuit and upon becoming extinguished, as sequence switch 110 leaves position 14 in response to the removal of the called subscriber's receiver from the 20 switch hook, notifies the operator that he has answered. A complete talking circuit is now established and the calling and called subscribers may converse with each other. 25 With sequence switch 110 in position 16 a circuit is closed from subbattery through the lamp 125, resistances 123 and 122, upper right-hand contact of sequence switch spring 127 (15+17), lower left-hand contact of said spring (2+16) to ground. The lamp 125, however, is not illuminated at this time due to the fact that it is shunted out by the following circuit closed by the relay 116½. As sequence switch 110 leaves position 30 35 armature of said relay, lower right-hand contact of sequence switch spring 129 (16), resistances 124 and 122 to ground at the lower left-hand contact of spring 127. 40 *Release of the connection.*

When conversation has been completed and the subscribers replace their receivers to the switch hooks, the supervisory relays 115 and 116 are released. These relays release the shunt circuits from around the lamps 131 and 125, permitting their illumination to advise the operator that both subscribers have hung up their receivers. She thereupon seizes the plug 104 and withdraws it from the jack of the calling line. The removal of the plug from the jack permits the deenergization of relays 102 and 109. Relay 109 opens the holding circuits of relays 200 and 201, and these relays retract their armatures. Relay 109 also closes a circuit from battery through the left-hand winding of relay 113, conductor 172, inner right-hand armature and back contact of relay 205, conductor 164, right-hand contact of sequence switch spring 111 (2+18). As soon as the office selector sequence contact and left-hand armature of relay 219, back contact of relay 220 to subbattery. Relay 113 becomes energized and locks up in a circuit from battery through the right-hand contacts of spring 704, the contact and armature of relay 220 to subbattery. Relay 113 becomes energized and locks up in a circuit from battery through the removal of this potential causes in the well- 45 50 55 60 65 70 75 80 85 90 95 100 105 110 115 120 125 130

known manner the release of a relay in the circuits of the incoming selector switch, which in turn brings about the release of said switch. The restoration of the incoming switch also causes the final selector switch to be returned to its normal position.

10 *Operator responds to a second call while her telephone set is connected to the first cord circuit.*

The case will next be considered in which the operator, in response to a second call, inserts the plug of a second cord circuit in the 15 jack of the calling line while her telephone set is connected in talking relation to the first cord circuit. Provided the operator herself does not cause the disconnection of her telephone set from the first cord circuit, 20 such connection remains, as has been seen, until the register sender has completed its functions in controlling the selective switches at the end of which time her telephone set is automatically disconnected in 25 response to a condition set up by the sender. While the register sender is functioning, however, other calls may appear at this operator's position making it necessary for her telephone set to be placed in talking relation 30 to the next cord circuit which she may choose in answering a subsequent call prior to the time said telephone set would normally be disconnected and rendered free under the control of the register sender. To this 35 end the circuits are so arranged that the simple act on the part of the operator in the insertion of the plug of a second cord circuit in the jack of the second calling line causes, automatically, the disconnection of her telephone set from the first cord and the connection of the same in talking relation to the second cord circuit. In view of the fact 40 that the restoration of the cord finder switch to disassociate the register sender after it has completed its operation depends upon a condition created simultaneously with the disconnection of the operator's telephone set from the cord under the control of the sender, it becomes necessary when the operator's telephone set is disconnected in advance, as by the act of answering a second call, to bring about said condition also in advance, whereby when the sender has finally completed its switch controlling functions 45 it will find such condition already prepared and will be detached from the cord circuit.

Assume then that while the operator's set 50 210 is connected through the armatures and contacts of relay 203 to the cord circuit, shown in the drawing, and while the register sender is controlling the switches, a second call is initiated and the operator in response thereto inserts the plug 104 of a 55 second cord circuit in the jack of the second

calling line. The insertion of the second plug in the jack of the calling line causes the energization of relays 109 and 200, individual to the second cord circuit. At this time it will be recalled a circuit exists leading from battery through the winding of marginal relay 206, left-hand armature and front contact of relay 207, winding of relays 202 and 203, individual to the first cord circuit, to ground at the contact and right-hand armature of relay 202. The marginal relay 206 and relay 207 are common to all cord circuits, as indicated by the multiple tap 221, and, consequently, the energization of relay 200, belonging to the second cord circuit, causes the completion of a circuit from battery through the winding of relay 206, left-hand armature and contact of relay 207, thence over conductor 221, through the winding of relay 202 of the second cord circuit, left-hand armature and back contact of relay 201 of the second cord circuit to ground at the left-hand armature and contact of relay 200 of the second cord circuit. This latter circuit is in parallel relation to the circuit which already exists through the windings of relays 202 and 203, belonging to the first cord circuit, and since its resistance is comparatively low the flow of current through relays 202 and 203 of the first cord circuit is so reduced as to permit the release of these relays. Relay 203, on releasing, disconnects the operator's telephone set 210 from the first cord circuit. Relay 202 of the second cord circuit, being included in the low resistance branch of the series parallel circuit through the common marginal relay 206, operates and in turn causes the operation of relay 205, individual to the second cord circuit. From this point 100 on the operation of relay 201 and the consequent energization of relay 203 of the second cord circuit, for the purpose of connecting the operator's telephone set 210, proceeds in the manner already discussed in 105 connection with the first call.

Thus, when parallel circuits are established, one leading through the windings of relays 202 and 203 of one cord circuit, and the other leading only through the winding of relay 202 and thence directly to ground at another cord circuit, the former relays are shunted out and cause the disconnection of the operator's telephone set from the cord circuit to which they are individual. It was hereinbefore mentioned that the marginal relay 206, which is common to all cord circuits, does not operate when it is included in a circuit with the relays 202 and 203 of only one cord circuit. But when a second cord is taken for use and the above described parallel circuit is closed through the winding of relay 202 of such second cord, the total resistance over the parallel paths is so reduced 110 115 120 125 130

that sufficient current now flows through the common relay 206 to permit its energization. This series parallel circuit is maintained momentarily until the relays 202 and 203 of the first cord circuit are shunted out and relay 202 releases its armatures. During the momentary closure of the series parallel circuit through the winding of relay 206, said relay operates and in so doing completes a circuit from subbattery through its right-hand armature and contact, conductor 218; normal contacts at the right-hand armature of relay 302, winding of said relay, lower right-hand contact of sequence switch spring 322 to battery. The relay 302, which in the normal operation is energized by means of the circuit, hereinbefore traced, closed at the right-hand armature and contact of relay 207 at the time the sender has completed its switching controlling functions, is now operated in advance by the marginal relay 206, locks up and remains in this condition ready to bring about the restoration of the cord finder switch and the release of the sender as soon as such sender has reached the completion of its operations. The release of the sender in the present case need not be redescribed since it takes place in precisely the same manner as above explained when the cord finder sequence switch has reached position 17 and the sender sequence switch has advanced into position 1. As soon as relays 202 and 203, belonging to the first cord circuit, have deenergized, the marginal relay 206 also releases its armatures since it is now only included in series with the relays 202 and 203 of the second cord circuit, the current flowing through this single branch not being sufficient to maintain said relay 206 operated.

Should the operator wish to disconnect her telephone set from the cord circuit for any reason without waiting for it to be disconnected automatically by the register sender, she may do so by depressing her listening out key 215. The operation of key 215 completes a circuit from battery through the winding of relay 207, left-hand contacts of key 215 to subbattery and ground. As has been seen, relay 207 opens the circuit of relays 202 and 203 which become deenergized, and relay 203, at its armatures and contacts, opens the circuit leading to the operator's telephone set 210. At the right-hand contacts of key 215 a circuit is closed to conductor 218 for the energization of relay 302 so that the register sender may be released from the cord circuit as soon as it has finished controlling the switches.

If the operator wishes to listen in on any cord circuit from which her telephone set has already been disconnected, she may by operating the listening in key 216, individ-

ual to such cord. The actuation of key 216 completes a circuit from ground through the contacts of this key, front contact and left-hand armature of relay 201, the relay 201 being energized since the plug of the cord to which it is individual is inserted in the jack of a calling line, winding of relay 202, contact and left-hand armature of relay 207, winding of marginal relay 206 to battery. Relay 202 operates and, as above explained, closes a circuit for relay 203, which operates as soon as key 216 is released and in turn connects the operator's telephone set 210 to the conductors 105 and 106 of the desired cord circuit.

Should the operator desire to wipe out the connection at any time during the establishment thereof, she may do so by operating the disconnect key 209. Key 209 completes a circuit from subbattery through its left contact, upper contacts of sequence switch spring 141, closed in some position between positions 2 and 13, inner right front contact of relay 205, conductor 172, left winding of relay 113 to battery. Relay 113 operates and locks through its right hand winding and contact to ground at the spring 135. Assuming that the switch 110 is in some position prior to position 7, a circuit is now closed from battery through the winding of magnet 110, upper right contact of spring 136 (2+7), upper left contact of said spring (2+10) to subbattery at the left contact of relay 113. Sequence switch 110, by means of this circuit, moves into position 8. In position 8, a circuit is closed from battery through the winding of power magnet 148, lower right contact of spring 136, (8), upper left contact of said spring (2+10) to subbattery at the left contact of relay 113. When the switch 150 is fully restored to its normal position, a circuit is closed from subbattery through the upper right of spring 135 (3+6) brush 157, segment 163, upper right contact of spring 138 (4+18), winding of magnet 110 to battery. In this circuit, the magnet 110 is energized and advances the sequence switch from position 8 into position 1. Following this, the operator may remove the plug 104 from the jack or she may set up a connection anew.

Allotment of register senders.

An explanation will now be given of the manner in which the register senders are allotted for use by the allotter switch 320. Assume that the register sender shown in detail in the drawing, which is allotted in position 1 of the allotter switch 320, has been taken for use, as hereinbefore explained. When the cord finder sequence switch 310 of this register sender unit reaches position 8, which it assumes following the release of

the operator's keys, a circuit is closed from battery through the winding of magnet of allotter switch 320, upper contacts of sequence switch spring 311 (8+17), lower 5 right-hand contact of sequence switch spring 330 of the allotter switch, closed in position 1, to subbattery. The allotter switch 320, therefore, moves out of position 1 and into position 2. Position 6 is the allotting 10 position of the next register sender unit. If any one of the remaining register sender units happens to be idle at this time, the cord finder sequence switch 310 thereof will be standing in position 18. Consequently, 15 a circuit is closed from battery through the winding of allotter switch magnet 320, upper right-hand contact of spring 332 (2), thence over the particular parallel circuit which leads to the right-hand contact of the 20 spring 325 of sequence switch 310, belonging to the idle unit closed in position 18, to subbattery. The allotter switch 320 moves from position 2 into position 6. If the idle register sender unit is the one allotted in 25 position 6 of the allotter switch 320, said allotter switch comes to rest and a circuit is closed from battery through the winding of sequence switch 310 of such idle unit, upper right-hand contact of a spring corre- 30 sponding to sequence switch spring 306 (18), thence over conductor 364 to the lower left-hand contact of spring 330, closed in position 6, to subbattery. The sequence switch 310 of the idle register sender unit is ener- 35 gized in this circuit and moves into position 1 where it is taken for use when the next call is answered by the operator.

If the second register sender unit, which is allotted in position 6 of the switch 320, 40 happens to be busy when the allotter switch reaches position 6, a circuit is closed from battery through the winding of the magnet of said allotter, thence through the upper contacts of a sequence switch spring corre- 45 sponding to spring 311, conductor 364, lower left-hand contact of spring 330 (6) to subbattery, moving switch 320 out of position 6 and into position 7. Since under the assumption some one of the senders is idle, 50 as, for example, the sender allotted in position 12 of the allotter switch 320, a circuit is now closed from battery through the winding of the magnet of allotter switch 320, upper right-hand contact of spring 332 55 (7), thence to the right-hand contact of spring 325 of the sequence switch 310, belonging to the idle sender unit, to subbattery. Allotter switch 320 thereupon moves from position 7 into position 12. In this 60 position the sequence switch 310 of the idle register sender unit is driven from its waiting position 18 into position 1 by means of a circuit from battery through the winding of magnet of sequence switch 310, upper 65 right-hand contact of its spring 306 (18),

thence over conductor 364, upper left-hand contact of spring 330 (12) to subbattery.

Office selector switch advances to the overflow position.

In giving a detailed description of the establishment of a connection, it was previously considered that the office selector switch, shown in Fig. 7 at the time of performing its trunk hunting operation, succeeded in finding an idle trunk in the desired group. The assumption will now be taken, however, that at the time the trunk hunting operation is made all trunks in the desired group are busy and consequently the brushes 721, 722 and 723 are driven over the entire group of terminals to the overflow position. When the brushes 721, 722 and 723 are standing on the overflow terminals, the commutator brush 742 is also in engagement with a metallic segment of the commutator 745. It will be recalled that the sender sequence switch 610 advances into position 9 immediately following the completion of group selection at the office switch, and that the sequence switch 710 is in position 6 during the trunk hunting operation which follows thereafter. When the brushes 721, 722 and 723 reach the overflow terminals no ground potential is found on the test terminal thereof, and consequently the holding circuit of relay 700 is opened to open the circuit of the updrive power magnet 718, causing the brush shaft 720 to cease its upward movement. Relay 700 also completes the above traced circuit for driving the sequence switch 710 out of position 6 and into position 8. With the sender sequence switch in position 9 and the office sequence switch 710 in position 8, a circuit is closed from battery through the left-hand winding of marginal relay 603, winding of sensitive relay 602, outer armature and contact of relay 604, lower left-hand contact of sequence switch spring 617 (9+10), upper left-hand contact of said spring (6+11), and thence, as hereinbefore traced, over district selector brush 152, terminal 155, lower left-hand contact of sequence switch spring 714 (8+9), resistance 715 to subbattery and ground. As before explained the resistance 715 is sufficiently high to prevent the operation of the marginal relay 603 but does permit the operation of relay 602 to cause the advance of the sender. In the present case, however, since the office switch has gone to the overflow position a shunt circuit is closed through the upper right-hand contact of sequence switch spring 714 (8+9), commutator 745, brush 742, left-hand contact of sequence switch spring 702 (7+10) to subbattery. This latter circuit shunts out the resistance 715 and provides a low resistance path through the left-hand winding of marginal relay 603. Consequently, relay 603

energizes in series with relay 602. Relay 603 locks up through its right-hand winding and contact and right-hand armature to subbattery through the contact of sequence switch spring 613 (8+18). Relay 602 causes the advance of the sender sequence switch spring 614 (11+18), brush 344, terminal 350, conductor 356, lower left-hand contact of sequence switch spring 136 (11), upper right-hand contact of said spring (11+17), winding of sequence switch magnet 110 to battery. Sequence switch 110, by means of this circuit is advanced out of position 11 and thence into position 14, as hereinbefore described. It will be recalled that sequence switch 110 is driven from position 9 into position 11 due to the deenergization of relay 120, the circuit of which is opened at the lower right-hand contact of sequence switch spring 617 as the sender sequence switch 610 moves out of position 8 following the completion of office group selection. On leaving position 11 sequence switch 110 opens the holding circuit of relay 300 which becomes deenergized and completes a circuit from battery through the winding of sequence switch magnet 310, upper left-hand contact of sequence switch spring 307 (8+16), back contact and right-hand armature of relay 300 to subbattery, driving sequence switch 310 out of position 8 and into position 17. With sequence switch 310 in position 17 a circuit is closed from battery through the winding of relay 601, lower right-hand contact of sequence switch spring 308 (17), upper left-hand contact of said spring (1½+17), back contact and right-hand armature of relay 300 to subbattery and ground. Relay 601 operates and closes a circuit from subbattery through its outer right-hand armature and contact, lower left-hand contact of sequence switch spring 615 (2+18), winding of sequence switch magnet 610 to battery, moving said sequence switch out of position 11 and into position 1. When sequence switch 610 reaches position 1 the circuit hereinbefore traced is closed for the energization of relay 207 which brings about the disconnection of the operator's telephone set and also causes the energization of relay 302. Relay 302 closes the above traced circuit for the downdrive power magnet 337 of the cord finder switch and the cord finder is restored to its normal position after which the sequence switch 310 is moved into position 18 and relays 601 and 302 are deenergized.

5 Referring to the office switch in Fig. 7

6 explained, when sequence switch 710 reaches position 8 by means of the circuit closed by sequence switch 110 in position 11 and sequence switch 610 in position 9. Relay 700, 70 causes the advance of the sender sequence switch 710 out of position 9, into position 10, and thence into position 11, as hereinbefore described. Upon reaching position 11 a circuit is completed from subbattery through the left-hand armature and back contact established a circuit for driving sequence switch 710 into position 10. A circuit is now closed from battery through the winding of sequence switch magnet 710, contact of sequence switch spring 709, closed in positions 10 and 12, commutator 745, brush 742, left-hand contact of sequence switch spring 702, closed in positions 7+10 and positions 12+5 to subbattery. Sequence switch 710 is driven first into position 12 and then into position 17 by means of this circuit. Since the district sequence switch 110 has been driven, as explained, into position 14 due to the fact that relay 603 is energized in response to the overflow condition, a circuit is now established from ground, resistance 750, interrupter 751, upper left-hand contact of sequence switch spring 714 (17), terminal 155, brush 152, lower right-hand contact of sequence switch spring 145 (11+16), lower left-hand contact of said spring (12+16), winding of relay 116, lower right-hand winding of repeating coil 117 to battery. On the first closure of the interrupter 751 relay 116 is energized and completes the circuit hereinbefore traced for driving the sequence switch 110 out of the ringing position 14 and into the talking position 16. In position 16 the supervisory lamp 125 is lighted in a circuit from battery through said lamp, resistances 123 and 122, upper right-hand contact of sequence switch spring 127 (15+17), lower left-hand contact of said spring (2+16) to ground. Each time the interrupter 751 closes following the arrival of sequence switch 110 in position 16, relay 116 attracts its armature and closes a circuit from subbattery through its contact and armature, lower right-hand contact of sequence switch spring 129 (16), resistances 124 and 122 to ground through the contacts of sequence switch spring 127. This circuit closed by relay 116 shunts the lamp 125 and causes it to be illuminated and extinguished intermittently. The operator, observing the flashing of lamp 125, knows that the connection has failed by reason of the fact that all trunks of the group at the office switch are busy. She thereupon listens in and notifies the calling subscriber that the connection cannot be obtained and then proceeds to release the connection.

7 What is claimed is:

8 1. In a telephone system, an operator's position, a telephone set and a cord circuit

- thereat, selective switches, said cord circuit and switches serving to extend talking connections, a register sender for controlling the movement of said switches, a connecting relay for said cord circuit, means effective when the cord is taken for use to operate said connecting relay to connect the telephone set to said cord, means for associating said sender with the cord, disconnecting means operated by said sender to disconnect said telephone set, releasing means for said sender, and means operated by said disconnecting means for rendering the sender releasing means effective.
15. 2. In a telephone system, an operator's position, a telephone set and a cord circuit thereat, selective switches, said cord circuit and switches serving to extend talking connections, a register sender for controlling the movement of said switches, a connecting relay for said cord circuit, means effective when the cord is taken for use to operate said connecting relay to connect the telephone set to said cord, means for associating said register sender with the cord, a second relay, means operated by said register sender when it has completed its switch controlling functions for operating said second relay, said second relay opening the circuit of said connecting relay to disconnect the telephone set from said cord, and means operated by said second relay for releasing the register sender to disassociate the same from said cord circuit.
20. 3. In a telephone system, an operator's position, a telephone set and a cord circuit thereat, selective switches, said cord circuit and switches serving to extend talking connections, a register sender for controlling the movement of said switches, a connecting relay for said cord circuit, means effective when the cord is taken for use to operate said connecting relay to connect the telephone set to said cord, means for associating said sender with the cord, disconnecting means operated by said register sender when it has completed its switch controlling functions to disconnect said telephone set, releasing means for said sender, and means operated by said disconnecting means for rendering the sender releasing means effective.
25. 4. In a telephone system, an operator's position, a telephone set and a cord circuit thereat, selective switches, said cord circuit and switches serving to extend talking connections, a register sender for controlling the movement of said switches, a connecting relay for said cord circuit, means effective when the cord is taken for use to operate said connecting relay to connect the telephone set to said cord, a switch for associating said register sender with the cord circuit, disconnecting means operated by said sender to disconnect said telephone set, and means rendered effective by said disconnecting means for releasing said last named switch to disassociate the register sender from said cord circuit.
30. 5. In a telephone system, an operator's position, a telephone set and a cord circuit thereat, selective switches, said cord circuit and switches serving to extend talking connections, a register sender for controlling the movement of said switches, a connecting relay for said cord circuit, means effective when the cord is taken for use to operate said connecting relay to connect the telephone set to said cord, means for associating said register sender with the cord circuit, disconnecting means operated by said register sender to disconnect the telephone set from the cord circuit, and means rendered effective by said disconnecting means for releasing the register sender to disassociate the same from the cord circuit.
35. 6. In a telephone system, subscribers' lines, a cord circuit for extending said lines, selective switches for further extending said lines, a telephone set at the operator's position, a register sender for controlling the movement of said switches, a connecting relay for said cord circuit, means responsive to the connection of said cord circuit with a subscriber's line for operating said relay to connect the telephone set to said cord, means for associating the register sender with the cord circuit, disconnecting means operated by said register sender to disconnect the telephone set from the cord circuit, and means rendered effective by said disconnecting means for releasing the register sender to disassociate the same from the cord circuit.
40. 7. In a telephone system, subscribers' lines, a cord circuit for extending said lines, selective switches for further extending said lines, a telephone set at the operator's position, a register sender for controlling the movement of said switches, a connecting relay for said cord circuit, means effective when the cord circuit is connected to a subscriber's line to operate said connecting relay to connect the telephone set to said cord, means effective in response to the connection of the cord circuit to the subscriber's line for associating said register sender with said cord, disconnecting means operated by said register sender to disconnect said telephone set from the cord circuit, and means rendered effective by said disconnecting means for releasing said register sender to disassociate the same from the cord circuit.
45. 8. In a telephone system, an operator's position, a plurality of cord circuits and a telephone set thereat, selective switches, said cord circuits and switches serving to extend talking connections, a register sender for controlling the movement of said switches,

a connecting relay for each of said cord circuits, means effective when a cord is taken for use to operate the connecting relay in circuit, means effective when a second cord for use to operate the connecting relay in circuit is taken for use to shunt the individual thereto to connect the telephone connecting relay individual to the first cord set to said cord, means for associating the circuit and to operate the connecting relay register sender with the cord circuit taken individual to said second cord for transfer for use, disconnecting means operated by breaking the connection of said telephone set said sender to disconnect the telephone set from the first to the second cord circuit, from said cord circuit, releasing means for means operated simultaneously with the 65

second cord circuit, said common relay being operated simultaneously with the transfer of the connection of said telephone set, and means responsive to said common relay for causing the release of said register sender after said sender has completed its switch controlling functions to disassociate the same from said first cord circuit.

14. In a telephone system, an operator's position, a telephone set and a plurality of cord circuits thereat, selective switches, said cord circuits and switches serving to extend talking connections, a register sender for controlling the movement of said switches, a connecting relay for each of said cord circuits, a common marginal relay for all of said cord circuits, means effective when a cord circuit is taken for use for closing a circuit including said marginal relay for the connecting relay individual to said cord circuit for connecting said telephone set to said cord, means for associating said register sender with said cord, means effective when a second cord is taken for use for closing a circuit also including said marginal relay for the connecting relay individual to said second cord in shunt of the connecting relay to said first cord for causing the transfer of the connection of said telephone set from the first to the second cord circuit, said marginal relay being operated when simultaneously included in the circuits of said connecting relays, and means responsive to said marginal relay for causing the release of the register sender to disassociate the same from said first cord circuit after it has completed its switch controlling functions.

15. In a telephone system, a subscriber's line, an operator's position, a telephone set at said position, selective switches for extending said line, a register sender, a relay, means for rendering said relay effective to connect the subscriber's line to said telephone set, means controlled by the register sender for variably setting said switches, means operated by the register sender when all of said switches have been set for rendering said relay effective to disconnect the subscriber's line from said telephone set, and manually operable means at the operator's position for rendering said relay effective

to disconnect the subscriber's line from said telephone set.

16. In a telephone system, subscriber's lines, an operator's position, a telephone set at said position, a plurality of cord circuits thereat for extending said lines, selective switches for further extending said lines, a register sender for controlling the movement of the selective switches, a relay individual to each of said cord circuits, means operated when a cord circuit is taken for use for rendering the individual relay effective to connect the telephone set to such cord circuit, means operated by the register sender for rendering said relay effective to disconnect the telephone set, and means operated when a second cord circuit is taken for use for rendering said first relay effective to disconnect the telephone set from the first cord circuit and for rendering the relay individual to said second cord circuit effective to connect the telephone set to said second cord circuit.

17. In a telephone system, an operator's position, subscribers' lines terminating in jacks at said position, a plurality of cord circuits terminating in plugs at said position for extending the subscribers' lines, selective switches for further extending said lines, a register sender for controlling the movement of the selective switches, a telephone set at the operator's position, a relay individual to each of said cord circuits, means operated in response to the insertion of the plug of one of said cord circuits in the jack of a subscriber's line for rendering effective the relay individual to said cord circuit to connect the telephone set to said cord circuit, means operated by the register sender for rendering said relay effective to disconnect the telephone set, and means operated in response to the insertion of the plug of a second cord circuit in the jack of a second subscriber's line for rendering the relay of said first cord circuit effective to disconnect the telephone set therefrom and for rendering the relay individual to said second cord circuit effective to connect said telephone set to said second cord circuit.

In witness whereof, I hereunto subscribe my name this 8th day of April, A. D. 1921.

FRANKLIN A. STEARN.
